DESK SET OF MARKING PENS AND INKWELL

Nathan R. Cline, 752 S. Belmont,
Wichita, Kans. 67218

Filed May 2, 1966, Ser. No. 2,102

Term of patent 14 years

Int. Cl. D19—02

U.S. Cl. D74—5

FIG. 1 is an exploded perspective view of a desk set of marking pens and inkwell showing my new design;
FIG. 2 is a front elevational view thereof; and
FIG. 3 is a side elevational view thereof.

I claim:

The ornamental design for a desk set of marking pens and inkwell, as shown.
